UNITED STATES PATENT OFFICE.

ORLA H. IMAN, OF CHICAGO, ILLINOIS, ASSIGNOR TO VIGTMANN & COMPANY, OF CHICAGO, ILLINOIS, A CORPORATION OF ILLINOIS.

FUSIBLE LINK.

1,120,817.

Specification of Letters Patent. Patented Dec. 15, 1914.

Application filed March 18, 1914. Serial No. 824,841.

To all whom it may concern:

Be it known that I, ORLA H. IMAN, a citizen of the United States, residing at Chicago, in the county of Cook and State of Illinois, have invented certain new and useful Improvements in Fusible Links, of which the following is a specification.

This invention relates to improvements in fusible links, and refers more particularly to fusible links used for effecting the automatic closing of doors or windows in case of fire, when the temperature of the link reaches a certain predetermined amount.

The salient objects of the present invention are to provide a fusible link which will be positive and certain in operation under all the conditions met with in practice; to provide a fusible link which in itself is furnished with means to positively insure its opening when the solder has fused, whether the link be subjected to tension or not; to provide a link which will be capable of sustaining a large amount of tensile load without danger of coming apart under normal conditions; to provide a link which will be proof against the clogging effects of calcimine, paint, grease, dust, or other dirt; to provide a fusible link which will be simple of construction and economical of manufacture, and in general an improved fusible link of the character referred to.

My invention consists in the matters hereinafter pointed out and described in connection with the accompanying drawings, in which—

Figure 1 is a plan view of my improved fusible link with a short length of chain attached to each end; Fig. 2 is an elevation of Fig. 1; Fig. 3 is a longitudinal section through the link proper; Fig. 4 is a section taken along the line 4—4 of Fig. 1; Fig. 5 is a view showing the various parts of the link in partially assembled position, prior to soldering; and Fig. 6 shows the three elements of the link in separated position.

Referring to the drawings, it will be seen that the link consists of three parts,—the two main separable elements 1 and 2, and the spring 3. The two main members 1 and 2 are both alike and are formed by means of suitable dies, preferably of phosphor bronze or other similar metal which will not corrode and yet will have considerable mechanical strength. Each of these main mem-

bers is substantially flat in general outline, 55 but has a flange formed up and extending almost completely around its periphery for the purpose of giving additional mechanical strength. Each part of the link has a large hole in the circular end portion for the reception of the chain 4 in which the link is interposed. These holes are reinforced with eyelets or gromets 5 in order to prevent the end links of the chain from tearing the relatively thin metal of the link.

As will be seen from an inspection of the drawings, the tail of each of the two halves of the link is punched at two places along the center line of the link to form a pair of cone-shaped projections 6 adapted to inter-nest with the cones of the companion member of the link. One of these cone-shaped protuberances is punched out of the metal and projects on one side of the link, whereas the other is formed on the reverse side; this being for a purpose which will hereinafter appear. Between the two members 1 and 2 of the link I place the spring 3, which is provided with a pair of holes 7 located the same distance apart as the cone-shaped projections in the tails of the two main parts of the link. The size of the spring is substantially equal to the amount of overlap of the two main members of the link, and, as shown in Fig. 5, its normal shape is 80 curved so as to force the parts of the link apart when it is inserted between them. It will be seen by an inspection of Figs. 3 and 5 that one of the projections in one half of the link passes through one of the holes in 90 the spring, and the corresponding cone-shaped projection on the other half of the link passes through the other hole in the spring.

In manufacturing the link, I assemble the 95 two main members of the link in internested relation, with the spring between them, and press the assembly tightly together with a pair of pliers provided with opposed points which thus cover up a very small amount of 100 the exposed surface of the link. Having dipped the link in a suitable flux, I immerse it in a bath of readily fusible solder which thus flows into the crevices of the link. The solder is set by plunging the link into cold 105 water, and it is then ready for the loading with additional solder. This extra loading of solder can be seen at 8, 9, 10 and 11 in

the drawings, and is applied by means of an ordinary hand-soldering iron, meanwhile taking care to see that the link itself is not heated up sufficiently to melt the solder around the spring and cause the link to come apart. There are a number of reasons for applying this additional load of solder to the edges of the joints of the link. In the first place, it strengthens the link materially at a point where it is weakest to resist bending strains; secondly, it prevents corrosion of the joints of the link, and, thirdly, it prevents any possible chance for the link to become sluggish in action by the clogging of the joints with calcimine, paint, or other dirt.

So far as I am aware, my improved link is the first one to be provided with a self-contained release spring in the separable joint of the link, and by employing this self-contained spring I obtain several advantages in protection and operation, which are as follows:—First, the instant that the solder of the link melts, the spring at once forces the two members apart, in spite of any clogging effect due to the presence of paint or calcimine, and regardless of whether there is a small or a large amount of tension on the chain to which the link is attached. In the second place, the spring itself imparts additional strength to the soldered joint since the holes in the spring engage the cone-shaped protuberances of opposite halves of the link. Thirdly, it provides the proper spacing between the two main members of the links to allow the cone-shaped protuberances to internest with each other properly. The cone-shaped protuberances I have found increase the strength of the link very materially. In fact, my improved link is capable of sustaining several times the load of an ordinary flat link having the same overlapping area but without the internesting cones. By providing a pair of the cones, I am enabled to assemble the parts of the link together so that they will always be in perfect register and proper alignment. This makes all of the links exactly alike and interchangeable.

I do not wish to be limited to the details of construction shown or described, except as specified in the appended claims.

I claim—

1. A fusible link, comprising two thin sheet-like members assembled in overlapping relation, a plate-spring interposed between said two members and normally tending to force said members apart, and readily fusible solder surrounding said spring and maintaining the two members of the link in assembled relation.

2. A fusible link, comprising two thin sheet-like members stamped into similar relief configuration and nested together in overlapping relation and united by readily

fusible solder, and a plate-spring interposed between said two members and normally tending to force them apart.

3. A fusible link, comprising a pair of thin sheet-like members each provided with a projection and a recess, the two being assembled in internested and overlapping relation, the projection on each of the members entering the recess in the other member, and a piece of sheet metal interposed between the two members and provided with a pair of apertures engaging the projections on the two overlapping members, and readily fusible solder uniting the surfaces of the interposed sheet and the overlapping surfaces of the two main members.

4. A fusible link, comprising a pair of similar thin sheet metal members each provided with a beveled projection and a beveled recess and assembled in overlapping and internested relation, the beveled projection of each member entering the beveled recess of the other member, a spring-plate interposed between said members normally tending to force them apart and provided with a pair of apertures each engaging a projection on one of the main members, and readily fusible solder uniting the surfaces of the spring and the overlapping surfaces of the two main members.

5. A fusible link, comprising a pair of similar thin sheet-like members each provided with a cone-shaped projection and with a cone-shaped recess on the same side of the member, the two members being assembled in internested and overlapping relation, the cone of each member entering the recess of the other member, a plate-spring interposed between the two members and provided with a pair of apertures each registering with and engaging a cone on one of the links, and readily fusible solder uniting the overlapping surfaces of the two main members.

6. A fusible link, comprising a pair of separable members having a pair of overlapping surfaces united by readily fusible solder, and provided with resilient means tending to force said members apart and acting in a direction at an angle to said surfaces.

7. A fusible link, comprising a pair of separable members having a pair of overlapping surfaces united by readily fusible solder and adapted to transmit tension in a direction substantially parallel with said overlapping surfaces, and provided with resilient means tending to force said members apart and acting in a direction at an angle to the direction of said tension.

8. A fusible link, comprising a pair of substantially parallel separable members having a pair of overlapping surfaces united by readily fusible solder and adapted to transmit pull in a direction substantially parallel to the overlapping surfaces of said

members, and a spring tending to force said members apart and acting in a direction at an angle to said surfaces.

9. A fusible link, comprising a pair of thin sheet-like members having a pair of overlapping substantially parallel surfaces united by readily fusible solder, and a spring

interposed between said overlapping surfaces and acting in a direction at an angle to said surfaces.
